DESIGN FOR A LINK CHAIN FOR A BRACELET OR THE LIKE

Michael Chernow, New York, N. Y.

Application April 8, 1947, Serial No. 138,235

Term of patent 14 years

(Cl. D45—4)

To all whom it may concern:

Be it known that I, Michael Chernow, a citizen of the United States and residing at New York, in the county of New York and State of New York, have invented a new, original, and ornamental Design for a Link Chain for a Bracelet or the like, of which the following is a specification, reference being had to the accompanying drawings, forming part thereof, and in which

Fig. 1 is a top plan view of a link chain for a bracelet or the like, showing my new design,

Fig. 2 is a side elevational view thereof, and

Fig. 3 is a perspective view on a larger scale showing one composite link element thereof.

I claim:

The ornamental design for a link chain for a bracelet or the like, substantially as shown.
MICHAEL CHERNOW.
